FLUID HEATER

Virgil W. Moray, New York, N. Y., assignor to
 Akwa Heaters, Inc., New York, N. Y., a corporation of New York

Application June 19, 1935, Serial No. 27,281

15 Claims. (Cl. 122—32)

This invention relates to fluid heaters and more particularly pertains to steam boilers and auxiliary fluid heating means combined therewith. More specifically, the invention relates to auxiliary water heating coils for standard and other types of steam boilers.

Heretofore auxiliary water heating coils for steam boilers have generally been installed by laying the coils on top of the boiler tubes and by bolting the coil head to the boiler tube sheet. In order to prevent leakage between the steam and water space of the boiler and the smoke box or combustion chamber, it has been necessary to employ a relatively wide flange on the head and a wide gasket or to use a narrow flange and gasket with a large number of bolts. This type of connection is very rigid and it is difficult, if not impossible, to prevent leakage at all temperatures during operation and when the boiler is out of service. Additionally, the coil head is subjected to corrosion as a result of the contact of the combustion gases with the metal of the coil head. Since the tubes of the coils are normally of copper or copper alloy, electrolytic action is set up at all points of contact between the copper coils and the steel boiler tubes. This electrolytic action materially reduces the life of the boiler tubes, in some instances as much as one-half. A further disadvantage is the extreme difficulty of replacing defective boiler tubes without damaging the coils resting upon them.

The present invention overcomes the aforesaid disadvantages and others, and provides an elastic or resilient means for sealing and securing the coil heads against the boiler tube sheet, the securing and sealing force exerted being sufficient to hold the coil head tightly against the tube sheet at all times with sufficient force to prevent leakage and with sufficient elasticity so that expansion and contraction of the head is permitted without leakage even after rather severe contraction of the head as when the boiler is out of operation. The coil head is also protected against the corrosive action of the combustion gases by enclosing the head in a casing and means are provided for ventilation and cooling of the casing. In the form of the invention disclosed herein, the casing and coil head securing means are combined, as a result of which great compactness of the entire coil head assembly is obtained.

The invention further provides means for supporting the coils above the boiler tubes and entirely out of contact therewith. The character of the support is such that the coil is supported

throughout its entire length so that sagging of the coil is prevented. The support is also readily adjustable from outside of the boiler so that the coil may be maintained in the desired spaced relationship to the boiler tubes.

The invention further provides a multi-compartment fluid heating coil head which may readily be converted to provide for a single pass or a plurality of passes through the coil of the fluid to be heated, without the use of perforated partitions or partition plugs or the like and the attendant danger of leakage.

Other features and advantages of the invention will be perceived from the following description considered in connection with the accompanying drawings forming a part thereof and in which:

Fig. 1 is a partial longitudinal sectional view of a fire tube steam boiler having a longitudinally disposed auxiliary heating coil embodying, and supported in accordance with, the invention;

Fig. 2 is a sectional view on an enlarged scale, taken on line 2—2 of Fig. 1;

Fig. 3 is a sectional view taken on line 3—3 of Fig. 2;

Fig. 4 is a sectional view taken on line 4—4 of Fig. 2;

Fig. 5 is a sectional view taken on line 5—5 of Fig. 4;

Fig. 6 is a partial diagrammatic sectional view showing a coil mounted in a fire tube boiler having horizontally inclined boiler tubes;

Fig. 7 is a partial transverse sectional view of a fire tube steam boiler having a transversely disposed auxiliary heating coil supported in accordance with the invention, and

Fig. 8 is a sectional view of a detail showing one manner of connecting the supporting chain to the coil spacer plates.

Like characters of reference refer to the same or similar parts throughout the several views.

The invention will be disclosed in connection with a fire tube boiler and although the invention is particularly useful in boilers of this type, it will be understood that it is equally applicable to water tube boilers.

Referring to the drawings, reference character 10 designates the shell of a fire tube boiler having a pair of spaced tube sheets 11 (only one of which is shown), between which extends a bank of fire tubes 12. The front end of the shell 10 is closed by a cover 13 which forms with the tube sheet 11, a smoke box 14. In the form of the invention illustrated particularly in Figs. 1, 2 and 3, a water heating coil is disposed longi-

- tudinally of the boiler, that is to say, with the tubes of the coil disposed parallel or substantially parallel to the boiler tubes 12. Referring to Fig. 1, the water heating coil consists of a plurality of loop tubes 15 which are connected to a coil head 16. The tubes extend through an opening 17 in the tube sheet 11 which is large enough so that the copper tubes of the coil do not come in contact with the steel tube sheet.
- 10 The coil head 16 is disposed in the smoke box 14. The tubes 15 are suspended above the boiler tubes 12 out of contact therewith in accordance with the invention, to avoid any electrolytic action due to contact of the copper tubes of the coils with the steel tubes of the boiler. The tubes 15 of the heating coil pass through spaced tube holes in a plurality of spaced coil spacer plates 18 so that the tubes 15 may be supported throughout their entire lengths. The number 15 and disposition of these spacer plates may be varied to provide the support desired for the tubes of the coil. A chain 19 having its ends connected to the outermost spacer plates 18 of the coil, passes through the opening in an I-bolt 20 which is supported from the shell 10 of the boiler. Smaller chains 19' and 19'' connect the intermediate spacer plates 18 and chain 19. The I-bolt supporting means includes a nipple 21, the lower end of which extends through the shell 10 of the boiler and which is welded as indicated at 22, or otherwise secured to the shell. A steel disc 23 having a diameter substantially equal to the outside diameter of the nipple 21 rests upon the upper end of the nipple. The threaded upper end of the I-bolt 20 extends through a central aperture in the disc 23 and a nut 24 threaded on the end of the I-bolt bears upon the steel disc and supports the I-bolt therefrom. A cap 25 having sufficient interior volume to house the upper end of the I-bolt is threaded on the upper end of the nipple. With this arrangement it will be perceived that the heating coil is supported at a plurality of points and is suspended from a single point from the boiler shell. The distance the coil is suspended above the boiler tubes 12 may be readily varied by an adjustment of the nut 24 on the I-bolt 20. It will also be perceived that the adjusting means, that is the nut 24, is readily accessible from outside the boiler shell. All that is necessary is to remove the cap 25 and to apply a wrench to the nut.
- 55 A casing 26 of substantially rectangular configuration as shown, encloses the coil head 16 and is secured to the tube sheet 11 by welding as indicated, and serves not only to protect the head but also forms part of the means for securing the head to the tube sheet 11. The upper and lower walls 27 and 28 respectively of the casing 26 are provided with registering circular apertures and recesses, which receive cylindrical pins 29. A plurality of wedging members 30 engage spaced central portions of the pins 29 and the outer wall 31 of the head 16, and wedge the head against the tube sheet 11. A suitable gasket 32 is interposed between the head and the tube sheet to prevent leakage. In the form of the invention shown, the pins 29 are arranged to provide wedge contacting surfaces which may 60 be disposed at varying distances from the tube sheet 11, in order to provide flexibility in the securing of the head to the tube sheet to provide accommodation for manufacturing variations in the head and the casing. The pins 29 have spaced wedge-engaging sections 33 which

are rectangular in transverse cross-section. Each of the wedge contacting surfaces 34 is disposed at a different radial distance from the axis of the pin. For example, one of the surfaces 34 may be disposed at the desired radial distance from the axis of the pin and the other surface may be disposed respectively at radial distances which progressively increase by $\frac{1}{32}$ of an inch. In other words, one of the wedge contacting surfaces 34 may be disposed at the desired distance from the axis of the pin 29 with the surface 34 disposed normally to an axial plane of the pin and with each of the other wedge-contacting surfaces 34a, 34b and 34c disposed at radial distances which are $\frac{1}{32}$ of an inch greater than the distance the next preceding surface is disposed. These surfaces 34 may, of course, be disposed as desired with respect to distance from the axis and the number thereof may be varied as desired. In the form shown, two pins 29 are utilized and normally this number will suffice to adequately secure the header to the tube sheet, but any other number may be utilized. In some instances it may be found that a single pin having a plurality of cooperating wedges may be sufficient for the purpose. The wedges may readily be inserted from the open outer end of the head 16 which is closed by a cover 35. Cover 35 is forced into the casing 26 with sufficient tightness to prevent material leakage from the casing or it may be sealed with a suitable fire clay or cement.

If desired, plain circular pins without machined or otherwise prepared wedge-contacting surfaces may be employed, in which event the wedges will engage the cylindrical surfaces of the pins. Whether plain pins or pins of the character of pins 29 are employed, the pins will flex or spring outwardly with respect to the head 16 as indicated in the drawings, when the wedges are applied. This springing of the pins provides an elasticity or resiliency for the securing means which allows for expansion and contraction of the head so that the head is always held tightly against the tube sheet even when it is chilled and hence contracted. Leaks are thus prevented at all times whether the boiler is in or out of operation. With this arrangement, the necessity for the use of bolts and nuts and wide coil head flanges is eliminated. The wedges exert a tremendous pressure against the coil head and press it with such force against the gasket and tube sheet that leakage is prevented. With prior arrangements, the bolts holding the coil head to the tube sheet are often turned up so tightly in an effort to prevent or stop leakage that the bolts often are stripped and the prevention of leakage becomes impossible.

Fluid to be heated is supplied to the head 16 through an inlet pipe 36 and after flowing through the head and the coil tubes 15 wherein it is heated to the extent desired, it is conducted from the head through an outlet pipe 37. The inlet and outlet pipes may conveniently be threaded into the head as shown. In the form of the invention illustrated, means are provided for circulating air around the head 16 to assist in preventing corrosion of the material of the head. A pipe 38 having an inside diameter larger than the outside diameter of the inlet pipe 36 extends through the boiler shell 10 and is welded into the side plate of the casing 26. The outer end of the air conducting pipe 38 is opened to the atmosphere. A similar air conducting pipe 39 having its inner end welded into the upper

wall of the casing 26 encloses the outlet fluid pipe 37 and extends through the upper part of the boiler shell. With this arrangement, air will be circulated through the casing 26 and over the 5 coil head by thermo-syphon circulation, and thus cool the head and casing and prevent corrosion and destruction of the casing by the heat of the combustion gases. The air circulated through the casing will also carry away any moisture 10 formed by the sweating of the cold water pipe.

Another feature of the invention is the form of the lower wall 28 of the casing 26 which permits the heating coil 15 to be disposed in close proximity to the boiler tubes 12 without actually being 15 in contact therewith. With fire tube boilers this is of particular importance, since the boiler water level may be comparatively low and yet the tubes of the coil 15 may be completely submerged. To this end the bottom plate 28 is wedge-shaped in 20 longitudinal cross-section as shown in Fig. 1, with the smaller end of the plate disposed in contact with and welded to the tube sheet 11. With this arrangement it will be seen that the coil head 16 may be disposed more closely adjacent the 25 boiler tubes 12 than would otherwise be possible.

The coil head 16 is arranged to provide a plurality of fluid compartments each of which is separated from the adjacent compartment or compartments by imperforate walls so disposed 30 that one or more of the walls may be perforated to the end that the head may be converted to provide the number of fluid passes desired through the heating coil. In the form of head shown, the partitions are arranged to provide 35 either a single pass or a two-pass coil. It will be understood however, that the invention may be utilized to provide a number of passes larger than two if desired.

This feature of the invention is disclosed in 40 connection with a coil having fourteen single loop tubes or a coil having twenty-eight head connections. In some instances this number of tubes provides the greatest number which may be disposed in one head so far as auxiliary heating surface is concerned. However, the invention may 45 also be applied to a larger or a smaller number of tubes than disclosed.

Referring particularly to Figs. 2 and 3 of the drawings, the coil tubes 15 have their ends connected into the rear wall of the head so that the 50 ends of the tubes are arranged in horizontal rows which are superposed relatively closely adjacent each other, with the tubes in each row being disposed in vertical alignment with the tubes in all of the other rows. The arrangement of the tubes in each horizontal row is clearly indicated 55 in Fig. 2. For convenience in description, the tubes are numbered in Fig. 3 with the inlet and outlet end of each tube being given the same 60 number. For example, the outermost loop tube in the uppermost horizontal row is numbered 1 and has both its inlet and outlet ends numbered 1 in Fig. 3. Disposed inwardly in a horizontal plane of tube 1, is tube 2, and inwardly of tube 2, tube 3 is disposed. The same arrangement is 65 followed with respect to the other horizontal tube rows, the tubes being numbered altogether from 1 to 12. The space between the ends of tubes 3, 6, 9 and 12 is filled with vertically disposed loop 70 tubes designated 13 and 14 with the inlet and outlet ends of tube 13 disposed between the ends of tube 3 and the ends of tube 12 respectively. Tube 14 is disposed inside the tube 13 and has its inlet and outlet ends disposed respectively between the ends of tube 6 and tube 9.

The head 16 shown in Figs. 2 and 3 is initially formed with three imperforate partitions 43, 44 and 45. As viewed in Figs. 2 and 3, partition 43 is vertically disposed and has its inner end connected to the rear wall of the head between the second and third vertical tube rows numbering from the right hand end of the head. Partition 44 is also vertically disposed, parallel to partition 43, and has its rear end connected with or formed integrally with the rear wall of the head intermediate the fourth and fifth vertical tube rows numbered from the right hand end of the head. Partition 45 is also vertically disposed but is positioned at right angles to the partition 44 with which it is connected or integrally formed, and 10 is disposed parallel to the rear wall of the head and in spaced relationship thereto. The arrangement of these partitions is such that four head compartments are provided which are designated respectively A, B, C and D. To provide a two-pass coil, the partition 44 is perforated as indicated, to provide a relatively large circular opening of about the diameter of the inlet and outlet pipes 37 and 38. This may be done by means of a suitable tool inserted through the opening in 15 the side wall 40 of the head which is closed by a flush plug 41. With the partition 44 apertured as described, the flow through the coil will be from the inlet pipe 36 into compartment A 20 through the tubes connected to compartment A into transfer compartment B, thence into the inlet ends of the tubes of the second pass which are connected to the compartment B, into compartment C, through partition 44 into compartment D, and out through pipe 37. Since there 25 are fourteen loop tubes each having both ends connected to the head, it will be perceived that the compartments A and C should be arranged so that seven tubes have one end connected in each of these compartments. With the arrangement 30 shown, there are normally eight tubes connected in each of these compartments. The proper arrangement is provided by the use of pockets which serve to connect the excess number of tubes to the proper compartment. As shown, the inlet end of tube 2 is connected to compartment C by means of a pocket 46 formed by a wall 47 which connects with the rear wall of the head, the upper wall of the head and the partition 13, the arrangement being such that tube 2 discharges into compartment C. The inlet ends of tubes 13 and 14 are also connected to transfer compartment B by means of a pocket 48 formed by a wall 49 which surrounds both ends of these tubes and 35 connects them with the compartment B. With this arrangement, the ends of seven tubes, that is, tubes 1, 4, 5, 7, 8, 10 and 11 are connected to the compartment A and these tubes discharge fluid into transfer compartment B. The fluid then 40 enters seven tubes numbered 2, 3, 6, 9, 12, 13 and 14 and these tubes discharge the fluid into compartment C after which the fluid flows into compartment D through the opening in partition 44 and out of the head through pipe 37.

If it is desired that the head be arranged to 45 provide only a single pass for the fluid through the coil, partition 44 is not perforated, but partitions 43 and 45 are both apertured by suitable tools which may be inserted through the inlet opening of the head prior to the attachment of 50 the inlet pipe 36 and through the opening in the outer wall 31 which is closed by a plug 42 to provide openings which are substantially equal in flow area to the flow areas of the inlet and outlet pipes. With the partitions 43 and 45 apertured 55

and the partition 44 remaining imperforate, the flow will be from the inlet pipe 36 into both compartments A and C and through pipes 1 to 14 inclusive into the transfer compartment B, through the opening in partition 45 into compartment D, and thence through outlet pipe 37.

With this arrangement of the head of the heating coil, it will be seen that a standard form of head may be provided which may be readily altered or converted to provide a single pass or a two-pass flow of fluid through the coil. As previously mentioned, although the head disclosed may be converted only to either a single pass or two-pass header, nevertheless it will be understood that the invention may be applied also to provide passes other than single or two passes if desired.

As shown in Fig. 6, the heating coil may be arranged for installation with a boiler in which the boiler tubes 12 are horizontally inclined. The coil tubes 50 are arranged in superposed horizontal rows with the tubes in each of the rows from the lowermost to the uppermost rows of gradually increasing length. The particular lengths of the tubes of each row will be determined by the degree to which the boiler tubes are horizontally inclined. With this arrangement of the heating coil tubes, the coil may be disposed more closely adjacent the boiler tubes than would otherwise be possible and with all of the tubes of the coil completely submerged in the boiler water.

The heating coil supporting means of the invention may also be applied to heating coils which are disposed transversely to the boiler tubes. As shown in Fig. 7, the coil 51 is inserted through an opening in the side of the boiler shell 10 which is closed by a sleeve 52 forming a pocket through which the boiler water may circulate. The coil head 53 is secured to the flanged outer end of the sleeve 52. Water to be heated enters through an inlet pipe 54 and after passing through the tubes of the coil is discharged to the desired point of use through outlet tube 55. The tube coil is supported by a chain 56, the ends of which are connected to the endmost coil spacer plates 18, the chain passing through the opening in I-bolt 20. Intermediate shorter chains 56' have their ends connected to the central coil spacer plate 18 and to the chain 56 as indicated. With this arrangement it will be seen that the tubes of the coil 51 are supported throughout their entire length in spaced relationship to the boiler tubes and that the supporting means may be readily adjustable from outside of the boiler shell. The number and location of the coil spacer plates 18 with respect to the tubes may be varied as desired to provide the degree of support desired.

The supporting chains may be connected directly to the coil spacer plates 18 as indicated in Figs. 1 and 7 of the drawings and the chain may be insulated from these plates by suitable use of electric insulating material such as fiber, so that the chain does not come into direct contact with the coil spacer plates. Another arrangement which may be used for connecting the supporting chains to the coil spacer plates is illustrated in Fig. 8. Referring to this figure, the upper ends of the spacer plates are apertured and an I-bolt 57 is passed through the opening. The opening is provided with a fiber sleeve 58 having a length about the same as the thickness of the spacer plate. Fiber washers 59 and 60 are placed on the I-bolt at opposite sides of the spacer plate 18 and a nut 61 is threaded on the end of the I-bolt. The supporting chain 62 may be directly con-

nected to the end of the I-bolt as shown. With this arrangement the I-bolt is completely insulated from the spacer plate and from the tube of the coil so that electrolytic action and resulting corrosion of the several parts is prevented.

Thus it will be perceived that I have provided an elastic or resilient means for securing and sealing the coil head to the tube sheet, which is capable of exerting a tremendous pressure to press the coil head against the tube sheet with sufficient force to prevent leakage at all times whether the boiler is in or out of operation, and is also exceedingly compact. The coil head casing and the ventilation of the casing protects the head against corrosion and also prolongs the life of the casing.

The forms of the invention disclosed are to be considered as preferred forms. Changes may be made in the form, arrangement and disposition of the several parts without transcending the principles of the invention. Accordingly, it will be understood that the invention is not to be limited except by the scope of the claims appended.

What I claim is:

1. A boiler comprising a shell, tube sheets, boiler tubes extending between the tube sheets, a fluid heating coil extending through a tube sheet, a head for the coil, and means including a wedge cooperating with a resilient member secured at a fixed distance from the tube sheet for forcing the head against the tube sheet to seal the head thereon.

2. A boiler comprising a shell, tube sheets, boiler tubes extending between the tube sheets, a fluid heating coil extending through a tube sheet, a head for the coil, and means comprising a wedge cooperating with a pin secured at a fixed distance from the tube sheet for forcing the head against the tube sheet to seal the head thereon.

3. A boiler comprising a shell, tube sheets, boiler tubes extending between the tube sheets, a fluid heating coil extending through a tube sheet, a head for the coil, and means comprising a wedge cooperating with a pin having wedge contacting surfaces which may be disposed at varying distances from the tube sheet, the pins being secured at a fixed distance from the tube sheet for forcing the head against the tube sheet to seal the head thereon.

4. A fire tube boiler comprising a shell, tube sheets, fire tubes extending between the tube sheets, one of the tube sheets and the shell forming a smoke box at one end of the boiler, a fluid heating coil extending through said one tube sheet, a head for the coil disposed in the smoke box and a corrosion resisting casing spaced from and enclosing the head and disposed in the smoke box.

5. A fire tube boiler comprising a shell, tube sheets, fire tubes extending between the tube sheets, one of the tube sheets and the shell forming a smoke box at one end of the boiler, a fluid heating coil extending through said one tube sheet, a head for the coil disposed in the smoke box, and a corrosion resisting casing for the head secured to the tube sheet.

6. A fire tube boiler comprising a shell, tube sheets, fire tubes extending between the tube sheets, one of the tube sheets and the shell forming a smoke box at one end of the boiler, a fluid heating coil extending through said one tube sheet, a head for the coil disposed in the smoke box, and a corrosion resisting casing for the head having connections with the atmosphere to

provide circulation of air through the casing and over the head.

7. A fire tube boiler comprising a shell, tube sheets, fire tubes extending between the tube sheets, one of the tube sheets and the shell forming a smoke box at one end of the boiler, a fluid heating coil extending through said one tube sheet, a head for the coil disposed in the smoke box, a fluid inlet pipe for the head, a corrosion resisting casing for the head, a pipe surrounding the inlet pipe having one end connected with the interior of the casing and the other end open to the atmosphere, and means for conducting air from the casing.

8. A boiler having a shell, a bank of boiler tubes in the shell, a fluid heating coil in the shell, a flexible member for suspending the coil out of contact with the boiler tubes, means for supporting the flexible member from the shell, and means for adjusting the supporting means for varying the distance the coil is suspended out of contact with the boiler tubes.

9. A boiler having a shell, a bank of boiler tubes in the shell, a fluid heating coil in the shell, a flexible tension member connected to the coil at spaced points, and means supported by the shell and connected to the chain for suspending the coil out of contact with the boiler tubes.

10. A fluid heating coil comprising a plurality of tubes connected to a head and adapted to be disposed in a boiler above a bank of horizontally inclined boiler tubes with the coil tubes extending substantially parallel to the boiler tubes and disposed substantially horizontally, the tubes of the coil being of increasing length from the lowermost to the uppermost row.

11. A fluid heating coil comprising a head having a plurality of partitions therein disposed so as to divide the head into a plurality of fluid compartments, a plurality of loop tubes having their ends connected to the head in such manner that some of the tubes connect each compartment with another compartment, and a wall connecting with one of the partitions and providing a fluid pocket in the head into which one of said loop tubes discharges, said wall extending into one compartment and being disposed so that the pocket formed thereby communicates with an adjacent compartment.

12. A fluid heating coil comprising a head having a plurality of partitions therein disposed so as to divide the head into a plurality of fluid compartments, a plurality of loop tubes having

their ends connected to the head in such manner that some of the tubes connect each compartment with another compartment, and one or more walls forming fluid pockets, in the head with which one or more of said loop tubes connects, said walls being disposed in one or more fluid compartments and arranged so that the pockets formed thereby communicate with fluid compartments adjacent to said one or more compartments.

5

10

13. A boiler comprising a shell, tube sheets, boiler tubes extending between the tube sheets, a fluid heating coil extending through a tube sheet, a head for the coil, and means including a wedge cooperating with a member secured at a fixed distance from the tube sheet for forcing the head against the tube sheet to seal the head thereon.

15

14. A heat exchange coil including a head having a wall provided with tube holes therein, the head having inlet and outlet openings, a first partition extending from said wall and dividing the interior of said head into chambers, one of which communicates with one of said inlet and outlet openings, a second partition extending from said wall and spaced from the first partition and dividing said other chamber into first and second compartments, the first of which communicates with the other of said inlet and outlet openings, a third partition dividing said one chamber into third and fourth compartments, the third of which provides a transfer chamber enclosing a plurality of said tube holes, the fourth of which communicates with said one of the inlet and outlet openings, and tubes having their opposite ends in said tube holes, some of said tubes connecting the first and third compartments, others of said tubes connecting the second and third compartments, the arrangement being such that by providing an opening in the first partition the head will provide a plurality of fluid passes through the coil, or by providing openings in the second and third partitions the head will provide a single fluid pass through the coil.

35

40

15. A boiler having a shell, a bank of boiler tubes in the shell, a fluid heating coil in the shell, a flexible member for suspending the coil out of contact with the boiler tubes, means for supporting the flexible member from the shell, and means for adjusting the supporting means for varying the distance the coil is suspended out of contact with the boiler tubes, said adjusting means being accessible from outside the shell.
